WINDLASS.

No. 311,370.

Patented Jan. 27, 1885

UNITED STATES PATENT OFFICE.

SAMUEL T. RICHARDSON, OF BALTIMORE, MARYLAND, ASSIGNOR TO THE RICHARDSON MANUFACTURING COMPANY, OF SAME PLACE.

WINDLASS.

SPECIFICATION forming part of Letters Patent No. 311,370, dated January 27, 1885.

Application filed June 24, 1884. (No model.)

To all whom it may concern:

Be it known that I, SAMUEL T. RICHARDSON, a citizen of the United States, residing at Baltimore, Maryland, have invented new 5 and useful Improvements in Windlasses, of which the following is a specification.

This invention relates to windlasses for use on shipboard in dropping and weighing anchors, and for analogous purposes in various 10 situations.

The machine represented in the drawings may, if desired, be arranged between decks; and it consists of a pair of barrels or drums mounted loosely on a shaft supported in suitable bearings, means being provided for connecting one or both of said barrels rigidly to the shaft, so that they may rotate together, or so that only one can be used, if required. The machine also embraces mechanism for converting an oscillatory movement into a continuous rotation of one or both barrels, and means for arresting or retarding the backward rotation of said barrels in paying out the cable.

The invention consists in certain peculiarities in the construction and arrangement of parts, as hereinafter more fully set forth.

In the annexed drawings, illustrating my invention, Figure 1 is a front elevation of my improved windlass, partly in section, and Figs. 30 2 and 3 are sectional detail views.

The rotating axis or shaft A of this windlass is supported centrally in a bearing, a, secured to a post or standard, B, and its ends are journaled in bearings provided therefor in standards or posts C C.

On the shaft A are loosely mounted a pair of windlass-barrels, D D, and a pair of bevel-gears, E E, the latter having elongated hubs b, that abut against the central bearing, a, of 40 the windlass-shaft. The inner ends of the loosely-mounted barrels or drums D D are provided with an annular series of ratchet-teeth, c, and the outer faces of the loose gears E E have pivoted thereto a number of gravity-45 pawls, d d, adapted to engage with said ratchet-teeth. The outer end of each windlass barrel or drum D has a flanged periphery, e, and a hub, f. This hub is recessed on its outer side, as shown in Fig. 1, for the reception of nuts 50 g g, that are screwed upon a threaded portion,

h, of the shaft A, so as to prevent lateral movement of the windlass drum or barrel.

To each end of the shaft A is keyed a sliding clutch, F, having jaws or lugs i i, for engaging corresponding lugs, i' i', on the barrel-hub. The clutches F are each provided with an annular groove, k, for the engagement of a collar, m, attached to a lever, G, that is pivoted in bearings on the post or standard C, in which the end of the shaft is journaled. It 55 will be seen that by shifting the clutches F into proper position, either or both windlass-barrels can be connected rigidly to the shaft A, so as to rotate together or independently, as required. The pawls d d on both bevel-gears E E are arranged to point or work in the same direction, and are alternately brought 60 into engagement with the ratchet-teeth c on the opposite drums or barrels D by the oscillatory movements of the gears E. These bevel-gears E are actuated by an intermediate bevel-gear, H, that is journaled in any suitable manner in a plane at right angles with the gears E E and meshing therewith. The bevel-gear 65 H may be oscillated by detachable levers inserted in sockets I on the outer face of said gear.

It is obvious that when both windlass-barrels D D are connected to the shaft A by the clutches F F a continuous rotary movement 80 will be imparted to the barrels and shaft by the oscillating movements of the gears H and E E. When one gear E is moved forward by the gear H, the opposite gear E is moved back, and as the pawls d d point in the same 85 direction on both gears E it is apparent that as one set of pawls come into engagement with the adjacent ratchet-teeth c the other set of pawls are moved back with a sliding movement over their ratchet for a new hold. Power 90 is thus applied alternately to the barrels D D; but while both are connected rigidly to the shaft A a continuous rotary movement of both barrels will be produced.

If desired, either one of the windlass-barrels 95 can be rotated without moving the other. This is accomplished by sliding one of the clutches F out of engagement with the clutch-jaws i' i' on the adjacent-barrel and by holding the pawls d d of the gear E on that side of the 100

windlass out of engagement with the ratchet-teeth on the barrel that is to remain stationary. In order to enable the pawls *d d* to be raised simultaneously out of engagement with the ratchet, they are connected by means of a curved bar, *p*, Fig. 3, that is pivoted to the central pawl. This bar *p* has slotted ends for engaging pins on the outer pawls of the series, so that when the bar is raised all the pawls 10 are disengaged from the ratchet *c*. Corresponding perforations, *s s'*, are made in the bar *p* and gear *E*, for the reception of a pin that holds the bar and attached pawls away from the ratchet. Either one of the windlass-15 barrels *D* can thus be disconnected from its actuating-gear *E* and from the shaft *A*, so as to remain stationary while the other barrel or drum is being rotated.

Beneath each barrel or drum *D* is a guide-20 roller, *K*, having several annular grooves for guiding the cable while being wound, so that it will be laid on the drum or barrel in regular coils.

When it is desired to unwind the cable or 25 allow it to pay out freely—in lowering an anchor, for instance—the drum or drums *D D* may be permitted to rotate backward on the shaft *A* by disconnecting the clutches *F F* and by elevating the pawls *d d*, as before described.

30 The backward rotation of the drum or drums under the weight of the anchor will thus exert no action on the shaft *A* or gears *E* and *H*.

In order to control the speed of the unwinding cable, friction is applied to the drum or 35 drums *D* by means of a metallic friction-band or brake-strap, *L*, Figs. 1 and 2. This brake-strap or friction-band is placed in a groove formed in the flanged periphery *e* of the outer end of the drum.

40 By reference to Fig. 1 it will be seen that a portion of the friction-band is slotted, as shown at *t*, and another portion is reduced in width to pass through said slot, one portion of the band or strap being turned upward and the other portion down, as shown in Fig. 2. The upper end of the strap *L* is connected to the lower end of a rod, *M*, that is pivoted to a plate, *v*, secured overhead. The lower end of the strap *L* is attached to the upper end of a

45 rod, the lower end of which is screw-threaded and inserted in the threaded hub of a hand-wheel, *P*, that is connected to the upper screw-threaded end of a rod, *Q*, the lower end of which is pivoted to a plate, *w*, that is secured to the deck or floor. The rods *N* and *Q* are

50 screw-threaded in opposite directions, one being right hand and the other left, so that the band *L* can be tightened or loosened according to the direction in which the wheel *P* is turned.

55 60 By this means a sufficient degree of friction can be readily applied to the drums *D* to arrest or retard their backward rotation and thereby control the speed of unwinding the cable.

While the windlass is designed principally for use on shipboard in dropping and weighing anchor, it is obvious that it can be applied to advantage in other situations and for various purposes.

Having thus described my invention, what I claim is—

1. The combination, in a windlass, of the shaft supported in bearings, the clutches sliding on the shaft, the two loose drums having at their adjacent ends the annular series of ratchet-teeth and provided with clutches at 75 their other ends, the loose gear-wheels on the shaft, the gravitating pawls on the outer faces of the gear-wheels for automatically engaging the annular series of ratchet-teeth and the intermediate gear-wheel, substantially as described. 80

2. The combination, in a windlass, of the shaft mounted in bearings, the two drums loose on the shaft and provided with the annular series of ratchet-teeth, clutches for rigidly connecting one or both drums to the shaft, the gear-wheels loose on the shaft, the pawls on the gear-wheels automatically engaging the ratchet-teeth on the drums, and means for operating the gear-wheels to impart a continuous rotary movement to one or both drums, substantially as described. 85

3. The combination, in a windlass, of the shaft, the two drums loose thereon and provided with the annular series of ratchet-teeth, 95 clutches for rigidly connecting one or both drums to the shaft, the gear-wheels loose on the shaft, the pawls on the gear-wheels automatically engaging the ratchet-teeth on the drums, the intermediate gear for operating the 100 gear-wheels and imparting a continuous rotary motion to one or more drums, and the friction-brakes acting on the drums, substantially as described.

4. The combination, in a windlass, of a shaft, 105 two drums loose thereon and each provided with an annular series of ratchet-teeth, a pair of gear-wheels loose on the shaft and carrying pawls automatically thrown into engagement with the ratchet, means for holding the pawls 110 of either gear-wheel out of engagement with its ratchet, and gear for oscillating said gear-wheels, substantially as described.

5. In a windlass, the combination of the shaft *A*, drums or barrels *D D*, having ratchet-teeth *c c*, the loose bevel-gears *E E*, carrying pivoted pawls *d d* for engaging said ratchets, the bars *p p*, and the intermediate bevel-gear, *H*, substantially as described. 115

In testimony whereof I have hereunto set my hand in the presence of two subscribing witnesses.
